BATH MAT

Richard S. Gaugler, Dayton, Ohio

Application June 22, 1940, Serial No. 341,971

2 Claims.

(Cl. 4—185)

My invention relates to bath mats and has for its primary object the provision of an improved mat designed to prevent the bather from slipping on the finely finished and wet surfaces of the tub or shower to thereby lessen the possibility of injury resulting from such an occurrence.

Incident to this primary object of my invention are numerous more specific objects, the attainment of which all materially contribute to the achievement of the primary object. Among these more specific objects are the following:

1. The provision of a mat composed substantially of a porous textile fabric carried upon and extending across a peripheral loop formed of a flexible material heavier than water.

2. The provision of a mat wherein the peripheral loop supporting the porous fabric material is formed of a flexible material, for example, a wire spring, whereby during use, the mat is held in shape by spring tension and when not in use, may be twisted and folded upon itself once or twice to form a small, compact package capable of being inserted into a small sack for convenience in handling.

3. The provision of a mat wherein the coefficient of friction of the porous flexible material or fabric carried by the peripheral loop increases as the weight thereon increases to thereby prevent slipping of the bather and wherein the character of the material is such that it may be supported from the side walls of the tub or shower when not in actual use.

Other more specific objects will be apparent from the following description and claims, taken in connection with the following drawing wherein:

Fig. 1 is a plan view of one form of my improved mat;

Fig. 2 is a section taken on the line 2—2 of Fig. 1;

Fig. 3 is a longitudinal section taken on the line 3—3 of Fig. 2 showing the ends of the spring joined to form a loop;

Fig. 4 is a perspective view showing the flexibility of the loop;

Fig. 5 is a cross section corresponding to the section of Fig. 2, showing a modified form of my improved mat and taken on the line 5—5 of Fig. 6; and

Fig. 6 is a plan view of a modified form of my improved mat.

Specifically, with reference to Figs. 1 to 4, of the drawing, the loop 10 is formed of a wire spring 11, the ends of which are brought and fixed together in any suitable manner, for ex-

ample, by the friction joint shown in the form of a pin 12 forced within the convolutions of the spring. The textile fabric, cut into a sheet 13 conforming substantially to the shape of the loop 10, is secured to the loop 10 by means of the trim strip 14 extending continuously around the periphery of the sheet 13 and folded about the loop 10 and having its ends stitched to the sheet 13 and to each other as shown at 15. In this manner, the wire loop is concealed within the fold of the trim strip which is, likewise, made of a porous material.

As a modification, I have shown in Figs. 5 and 6 a sheet folded upon itself with its edges stitched to form a sack 13' much the same as a pillow case. An opening 16 through which the wire loop 10' may be inserted or removed, may be closed by the flap 17.

The wire spring 11 forming the peripheral loop on which the sheets 13 and/or 13' are carried, is heavier than water, thereby causing the mat to rest on the bottom of the tub or shower. Further, its tension tends to hold the sheets 13 or 13' stretched into their natural shape. The loop is, likewise, flexible and as a result, the mat may be twisted and folded upon itself as shown in Fig. 4. This characteristic of the loop is important in that by reason of this property as shown in Fig. 4, the loop may be twisted upon itself into the shape of the numeral 8 and then bent upon itself with the edges 18 and 18' adjacent each other to form two similar loops half the size of the original loop, and this twisting and bending may be repeated as desired to form a very small compact package. The mat in its folded form may be inserted into a small sack and sold in such a manner, and if desired may be washed and cleaned while in the small fabric sack. This characteristic of the loop facilitates the handling of the mat both during the original sale and during any washing operation that may be desirable.

In the modification shown in Figs. 5 and 6, the flap 17 may be opened and the spring 11' removed therethrough from the sack or double sheet 13'.

The textile fabric material used may be ordinary cotton fabric, for example, duck cloth, similar to that now used in curtains for showers. Preferably, the material is porous to allow the passage of water therethrough, and it may be either of the close or loose woven type. Preferably, it is of the type wherein the coefficient of friction increases as the weight thereon increases, so that the greater the weight supported

thereon, the greater is the tendency to prevent slipping.

My invention offers many advantages over prior known mats. It is simple and economical to manufacture. It may be folded into a small, compact unit or package and, consequently, is easy to handle as an article. It has a tendency to remain clean, yet if cleaning is necessary, this operation may be performed in a simple manner with the mat including the loop, in the form shown in Figs. 1 to 4, folded into a small unit insertable into a fabric sack. In the form shown in Figs. 5 and 6, the spring loop may be easily removed if desired and the folded sheet or sack may be washed as any ordinary article.

In both forms of my invention, the tension of the spring tends to hold the mat in its flat extended form.

Further, the mat is extremely efficient in operation. It may be easily moved about the tub, provided only a light force is applied thereto, whereas it is almost impossible to move if a heavy force is applied to press the fabric firmly against the surface of the tub or shower. This is probably due to the fact that a heavy force or weight tends to squeeze the water from beneath the mat, thereby causing the mat to contact directly with the tub or shower surface. It is this film of water which generally permits the ordinary mat to slip and conversely the absence of such a film prevents slipping.

After use, and while the mat is still wet, it may be placed on the side wall of the tub or shower and it will adhere thereto, even after it has dried out.

While my invention has been shown in two specific modifications, it should be understood that changes therein may be made within the scope of the following claims.

I claim:

1. A bath mat comprising a peripheral loop formed of a spring-like material flexible throughout its length and foldable and twistable upon itself to form irregular shapes, a single sheet of porous and flexible textile material substantially covering the space bounded by said loop, and a trim strip formed of a textile fabric folded about said loop throughout the length thereof and having its ends stitched to said sheet and to each other.

2. A bath mat comprising a peripheral loop formed of a spring-like material flexible throughout its length and foldable and twistable upon itself to form irregular shapes, a single sheet of porous and flexible textile material substantially covering the space bounded by said loop and secured at its periphery to said loop substantially throughout the length of said loop, said mat, due to the flexibility of said loop and said textile material, being foldable and twistable to form a small compact package.

RICHARD S. GAUGLER.
